UNITED STATES PATENT OFFICE.

FREDERICK MANKEY, OF WILLIAMSPORT, PENNSYLVANIA.

DESIGN FOR A PANEL.

SPECIFICATION forming part of Design No. 17,136, dated February 22, 1887.

Application filed December 30, 1886. Serial No. 223,050. Term of patent 7 years.

To all whom it may concern:

Be it known that I, FREDERICK MANKEY, of Williamsport, Lycoming county, Pennsylvania, have invented and produced a new and original Design for Panels, of which the following is a specification.

In the accompanying photographs, Figure 1 represents my design, and Figs. 2 and 3 arrangements or modifications thereof.

Similar letters of reference indicate like parts.

My design consists in the raised flat-surfaced parallelogram A, having rounded beveled or inclined edges. Parallel to each side of the parallelogram A are raised beads B C D E, having rounded upper surfaces. At the corners of the parallelogram A, and disposed between the extremities of the beads B C D E, are elevations F, having rounded or inclined upper surfaces. G is a flat-surfaced parallelogram having rounded beveled or inclined edges, and disposed with its long side parallel to the short side of the parallelogram A. The parallelogram G is narrower than the parallelogram A. The bead B lies between the parallelograms A and G. Parallel to the remaining sides of parallelogram G are beads H I J, having rounded upper surfaces. Between the extremities of said beads are the elevations N, similar to the elevations F. There is an intervening channel, K, surrounding the parallelogram A and separating it from the beads B C D E. A like intervening channel, L, surrounds the parallelogram G and separates it from the beads B H J I. Narrower channels, as M, separate the elevations F N from the extremities of the beads. Instead of showing a single parallelogram G, with its associated

beads H I J, elevations N, and intervening channels, at one end of the parallelogram A, 40 I may show two such parallelograms, one at each end of parallelogram A, as in Fig. 1, in which parallelogram G' is similar to G, the beads H' I' J' similar to the beads H I J, the elevations N' similar to elevations N, with 45 like intervening channels, L' M'. The bead D then appears between the parallelograms A and G.

I claim—

1. The design for a panel, substantially as 50 herein shown and described, which consists in the raised flat-surfaced parallelogram A, having rounded beveled or inclined edges, the surrounding channel K, beads B C D E, and elevations F, having rounded upper surfaces, 55 the raised flat-surfaced parallelogram G, having rounded beveled or inclined edges, the surrounding channel L, the beads H I J, and elevations N, having rounded upper surfaces, and the channels M. 60

2. The design for a panel, substantially as 65 herein shown and described, which consists in the raised flat-surfaced parallelogram A, having rounded beveled or inclined edges, the surrounding channel K, beads B D C E, and elevations F, having rounded upper surfaces, 70 the raised flat-surfaced parallelogram G G', having rounded beveled or inclined edges, the surrounding channels L L', the beads H I J H' I' J', and elevations N N', having rounded upper surfaces, and channels M M'. 75

FREDERICK MANKEY.

Witnesses:

C. F. MANKEY,
LEONHARD KNAUSS.
